UNITED STATES PATENT OFFICE

WILLIAM M. SHEEHAN, OF ST. LOUIS, MISSOURI, ASSIGNOR, BY MESNE ASSIGNMENTS, TO GENERAL STEEL CASTINGS CORPORATION, OF GRANITE CITY, ILLINOIS, A CORPORATION OF DELAWARE

LOCOMOTIVE MUD RING

Original application filed December 16, 1926, Serial No. 155,323. Divided and this application filed November 17, 1927. Serial No. 233,836.

My invention relates to new and useful improvements in locomotives and more particularly to the foundation ring or mud ring which is a metallic member shaped to correspond to the ground plan of the locomotive firebox, such as is shown in my copending application Serial No. 155,323, of which this is a division.

The present device is directed particularly to types similar to those locomotives in which the trailer trucks are arranged to take care of the pulling and buffing stresses. It has heretofore been customary to form the deck plate in a separate piece and bolt it to the rearward end of the mud ring.

The principal object of my invention is to provide integral means for the attachment of the cab sheets.

Another object is to provide a mud ring in which the inner and outer firebox sheets may be independently fastened.

A still further object is to provide a mud ring with shoulders which partially support the firebox sheets as well as serving for fastening surfaces.

With the foregoing and other objects in view, my invention consists in certain novel features of construction and arrangement of parts hereinafter more fully described and claimed, and illustrated in the accompanying drawings in which—

Figure 1 is a top plan view of my integrally formed mud ring and deck plate.

Figure 2 is a side elevation showing the arrangement of the parts in relation to a locomotive.

Figure 3 is a sectional view of the preferred form of mud ring shown in Figures 1 and 2 with the firebox sheets attached.

Figures 4, 5 and 6 are sectional views of mud rings of slightly modified forms.

The numeral 1 in the drawings indicates the main frame of a locomotive, 2 is a trailing truck connected at its forward end to the main frame 1 and provided at its rear end with draft rigging 3. This arrangement of the parts provides for the transmission of all pulling and buffing stresses through the trailing truck rather than through the rearward portion of the locomotive above the trailing

truck. Roller or rocker bearings 4 are mounted on the top surface of the trailing truck to support the rear end of the locomotive.

Mud ring 5 which is located over the upper edges of the ash pan 6 is provided on its forward end with depending feet 7. These feet 7 are preferably formed integrally with the mud ring and are adapted to slide longitudinally in a groove in the main frame 1 but held against lateral displacement. Along the lower rear edge of mud ring 5 and projecting rearwardly therefrom the deck plate 8 is formed as an integral portion of the mud ring construction. Deck plate 8 comprises side and end members of channel shape cross section and has longitudinal ties 9 of I-shaped cross section. Centrally located on the rear member of the deck plate 8, a bracket 10 is provided for the support of the cab sheet, not shown.

Integrally formed brackets 11 adapted to bear on rocker supports 4 are located underneath and at the side adjacent the point of merging between deck plate and mud ring portions of the frame. Suitable webbing 12 is provided to support the portion of these brackets which extend beyond the main body of the deck plate 8.

Provision is made for an automatic stoker, not shown, by providing brackets 13 on the forward portion of the upper surface of the longitudinal ties 9.

The lower edges of the inner and outer firebox sheets terminate at the mud ring 5. These sheets are suitably fastened to the mud ring, preferably by rivets.

Figures 3 to 6 inclusive illustrate cross sectional views of various styles of mud rings and the method of fastening the firebox sheets to this member. The mud ring 5 in Figure 3 is provided on its upper edge with inclined shoulders 14 to carry the inner and outer firebox sheets 15 and 16, respectively. Mud ring 5 is hollow and openings 17 are distributed throughout the lower surface to allow access to the interior of the ring for the purpose of installing rivets 18 which hold the firebox sheets in place.

Figure 4 illustrates a modification in which the lower edges of the firebox sheets are un-

bent. The mud ring 19 is substantially a hollow square in cross section with its lower side open. As in the mud ring 5, separate rivets are used for the attachment of the inner and outer firebox sheets 15 and 16 and access for the application of the rivets is through the open lower side 20.

The mud ring 21 of Figure 5 is similar to mud ring 5 except that the reinforcing bead 22 along the open lower edges is disposed outwardly instead of inwardly as the bead 23 illustrated in Figure 3.

In Figure 6 the mud ring 24 includes inclined side pieces as distinguished from vertical side pieces with inclined shoulders. The inclined side pieces terminate in reinforcing beads 25. Mud ring 24 is hollow and fully open as indicated at 26 along its lower side.

It will be noted that each of the mud rings illustrated in Figures 3, 5 and 6 presents an inclined surface for the connection of the firebox sheets. The lower edges of the firebox sheet are bent to coincide with the angle of the surface. This arrangement of parts besides providing separate means of attachment for the individual firebox sheets also removes a portion of the weight of the firebox sheets from the rivets. Since there is less strain applied directly to the rivets they will maintain rigid engagement between the parts, for a longer period of time without working loose.

It is to be understood that minor changes in the size, form and construction of the various parts of my device may be made and substituted for those herein shown and described without departing from the spirit of my invention as expressed in the following claims.

40 I claim:

1. A locomotive mud ring of substantially hollow cross section having an opening in its lower surface, an inclined shoulder on the upper surface of said mud ring, a firebox sheet having its lower edge bent to engage said inclined shoulder, and means extending through said shoulder for the rigid attachment of said firebox sheet to said mud ring, said means being accessible interiorly of said mud ring.

2. In a locomotive mud ring, an inclined shoulder on the upper surface of said mud ring, a firebox sheet having its lower edge inclined to overlie and rest upon said inclined shoulder, and means for the rigid attachment of the inclined portion of said firebox sheet to the inclined portion of said mud ring, said means extending through said inclined shoulder and the portion of said firebox sheet engaging said shoulder.

3. In a locomotive firebox, a mud ring of hollow cross section having an opening to the exterior of the firebox, a firebox sheet, a shoulder on said mud ring for the support of

said sheet, and means adapted to fasten said firebox sheet to said mud ring, said means being accessible from the exterior of the firebox through said opening in the mud ring.

4. In a locomotive firebox, inner and outer firebox sheets, a mud ring of substantially hollow cross section having shoulders extending beneath the lower edges of said sheets, and means for rigid attachment of said sheets individually to said mud ring, said means being accessible exteriorly of said firebox.

5. A locomotive mud ring of inverted U-shape and having a reinforcing bead along each of its lower edges, there being upwardly facing surfaces for supporting firebox sheets on the legs of said mud ring above said beads.

In testimony whereof I hereunto affix my signature this 22d day of Oct., 1927.

WILLIAM M. SHEEHAN.
